UNITED STATES PATENT OFFICE.

FRANK H. WRIGHT, OF CHATTANOOGA, TENNESSEE.

FURNACE.

1,099,682.

Specification of Letters Patent.

Patented June 9, 1914.

Application filed June 10, 1913. Serial No. 772,783.

To all whom it may concern:

Be it known that I, FRANK HOWARD WRIGHT, a citizen of the United States, and a resident of Chattanooga, in the county of Hamilton and State of Tennessee, have made certain new and useful Improvements in Furnaces, of which the following is a specification.

My invention relates to furnaces for general use, and more especially to coal burning furnaces in which the grate bars are apt to become very hot, and in which, as a consequence, it is desirable to cool the grate bars by passing air through them, and cause the air thus heated to assist the combustion of the fuel.

My invention further relates to means for handling the fuel during its passage through the furnace, and for equally distributing the air supplied into and through the fuel.

My invention further relates to mechanical means of different kinds employed for the purpose of improving the general efficiency of furnaces of this character.

Reference is made to the accompanying drawings forming a part of this specification, and in which like letters indicate like parts.

Figure 1 is a fragmentary section taken upon a vertical plane extending in the general direction of the length of the furnace and substantially centrally of said furnace. Fig. 2 is a cross section on the line 2—2 of Fig. 1, looking in the direction of the arrow. Fig. 3 is a detail showing in cross section, some of the grate bars employed, and also showing how the grate bars are supported. Fig. 4 is a fragmentary section similar to a portion of Fig. 3, but enlarged relatively thereto, and showing a ball bearing used for supporting some of the grate bars. Fig. 5 is an end view of the furnace showing the same partly in elevation and partly in section on the line 5—5 of Fig. 1, looking in the direction of the arrow. Fig. 6 is a fragmentary section on the line 6—6 of Fig. 1, looking in the direction of the arrow. Fig. 7 is a detail showing partly in perspective and partly in section a group of grate bars. Fig. 8 is a cross section showing a form of my furnace in which the fuel is fed obliquely downward from opposite sides toward the center. Fig. 9 is a view partly in section and partly in elevation showing another arrangement of the grate bars. Fig. 10 is a detail showing in eleva-

tion one device for supplying hot air to the hottest portion of the furnace. Fig. 11 is another form having provision for mechanically actuating the dumping grate, and also for adjusting said dumping grate at will. Fig. 12 is a view similar to Fig. 11 and showing still another form in which ordinary flat grate bars are used, together with mechanical means for actuating the dumping grate and mechanism under control of the operator for adjusting the dumping grate.

An arch 10 made of fire proof material is provided with a concave surface 11, and below this arch is a distributing nozzle 12 which has, in this instance, the form of a fish tail burner and is in communication with an air passage 13, the latter extending through the wall 14 of the furnace to a pipe 13^a, as shown more particularly in Fig. 5.

A fuel hopper is shown at 15 and is supported by aid of angle posts 16 extending vertically, and an end wall 17.

A horizontally disposed plate 18 is connected with the end wall 17 and with the side walls. Resting partially upon this plate and engaging the end walls 17 is a plate 19 made of fire proof material and sloping obliquely downward from the feed hopper. A floor 20 is provided for the feed hopper. Slidably resting upon this floor is a feeding head 21 which extends crosswise of the furnace. Pivotaly connected to this feeding head 21 are two pitmen 22, located upon opposite sides of the furnace. As the mechanism upon each side of the furnace is substantially a duplicate of the mechanism upon the other side, I will only describe the mechanism of one side. This is shown more particularly in Fig. 1.

Pivotaly connected with a pitman 22 is a lever 23 provided with holes 24. This lever is pivotally mounted upon a bracket 25 which is carried by the bottom 20 of the hopper and extends outwardly therefrom. A brace 26 extends from the outer portion of the plate 20 to the end wall 17. A pitman 27 is pivotally connected with the lever 23 by aid of some one of the holes 24. By moving the pitman 27 to different holes 24, the degree of swinging or angular movement of the lever 23 may be adjusted within certain limits, at the will of the operator.

The pitman 27 is connected at one of its ends with an eccentric 28, the latter being carried upon a revolute shaft 29. Another

pitman 30 similarly connected with another eccentric 30^a (see Fig. 5) is pivotally connected with a lever 31, provided with holes 32 and journaled upon a bracket 33 and thus 5 adapted to swing.

A pitman 34 is pivotally connected with the lever 31, and by aid of the holes 32 may be adjusted to different positions so that the pitman 34 receives different degrees of longitudinal movement as the shaft 29 is turned. 10 The end wall 17 is provided with a slot 35 through which the pitman 34 extends.

A number of stationary grate bars are shown at 36 and are spaced apart and located 15 parallel with each other, as may be understood from Fig. 1. Each grate bar 36 is flat upon its upper surface and is provided with eaves or overhanging edges 37, each of these being provided with openings 37^a of substantially semicircular form, as may be understood from Figs. 2, 6 and 7. Each grate bar is further provided with a body portion 38 having a substantially U-shaped cross section. This body portion rests upon semi- 20 circular lugs 39, which are located upon two stationary side bars, one of which is shown at 40. Extending downwardly from each of the hollow body portions 38 of the stationary grate bars are pipe sections 41, which are 25 connected to a trunk 42 having a general cylindrical form in cross section and adapted to receive air and deliver the same through the pipe sections 41 into the hollow grate bars. A number of grate bars 43 are sever- 30 ally provided with web portions 44, the general form of the latter being indicated in Fig. 2. Each grate bar 43 is provided with overhanging edge portions 45, the latter being provided with substantially semi-cylindrical openings or notches 46.

A number of conical necks 47 are mounted upon the side bars 40 and arranged in pairs, as will be understood from Fig. 2. Each pair of conical necks 47 is held in position by 45 bolts 48, these bolts serving as pivot pins. Journaled upon the pivot pins are levers 49, these levers being pivotally connected at their bottoms to two connecting rods 50, which extend substantially parallel with the 50 side walls of the furnace and are inclined, as indicated in Fig. 1. Each grate bar 43 is provided at each of its ends with a socket 51, the form of which may be readily understood from Fig. 4, and each lever 49 extends 55 loosely into one of these sockets.

Each grate bar 43 is further provided with a groove 51^a, and fitting into this groove is a ball 52. Each side bar 40 is further provided with a series of lugs 53, each of these 60 lugs being provided with a groove 54 into which the ball 52 is fitted. When the parts are in position, each grate bar 43 rests partly upon a ball 52 and partly upon the adjacent stationary grate bar 36, which, as above explained, is flat upon its top. With the parts

thus arranged, when swinging motion is given to the several levers 49, the grate bars 43 are each slid laterally with relation to its general length.

Extending practically across the interior 70 of the furnace are three grate bars 55, each having in cross section a substantially arcuate form, each of these grate bars being journaled at its ends by aid of pivots 56 upon the side bars 40, and thus adapted to rock. 75

Connected rigidly with each grate bar 55 is an arm 57, these arms at their lower ends being pivotally connected to a bar 58. This bar is provided with two slots 59, 60. Slidably located within the slot 59 is a pin 61. 80 This pin is mounted upon the end of a composite rod 62, the rod being provided with a turn buckle 63 whereby its length may be adjusted within reasonable limits. A pin 64 extends through the slot 60 and is carried by a shaker rod 65 which is of considerable 85 length and extends outwardly through a slot 35. When motion is communicated to the connecting rod 50 and transmitted through the composite rod 62 to the bar 58, a rocking 90 motion is communicated to the grate bars 55. This rocking motion thus communicated to the grate bars 55 is positive, as the bar 58 is heavy enough to keep the rods 62 in tension, and the pin 61 can move within the 95 slot 59. If, therefore, the shaker rod 65 be grasped at its outer end, that is, the left end according to Fig. 1, and pulled and pushed in the general direction of its length, the 100 grate bars 55 may be rocked independently 105 of whether the connecting rods 50 are in motion or not. By simply pulling upon the shaker rod 65 while the connecting rods 50 are stationary, the grate bars 55 may be tilted. This is for the purpose of discharging ashes and cinders into the bottom of the furnace. The bridge wall of the furnace is shown at 66 and carries a distributing head 67 made of fire clay or other appropriate fire proof material. This distributing head 110 is provided with a longitudinal passage 68, and with a number of jet openings 69 communicating with this passage.

A header is shown at 70 (see Fig. 5) and is connected by pipe sections 36^a with the 115 adjacent ends of the hollow grate bars 36. Extending upwardly from the header 70 is a pipe 13^a which communicates with the passage 13. This pipe 13^a is provided with a valve 71 for controlling the flow of hot air 120 into the furnace.

Each grate bar 36 carries a number of nozzles 39^a, each communicating with the hollow body portion of the grate bar and extending backwardly and upwardly therefrom, so as to discharge hot air between each movable grate bar 45 and the adjacent stationary grate bar 36 next in order below it and to its right according to Fig. 3. 125

The body portion 38 of each hollow grate 130

bar is provided with a number of small air holes 72 (see Fig. 7), for discharging air. Each hollow grate bar 36 is provided with grooves 73 extending across its top, each 5 groove having a substantially semi-cylindrical form. Each grate bar 43 is similarly provided upon its top with grooves 74 extending directly across it. The grooves 73, 74, are for the purpose of admitting air 10 beneath the surface of the fuel as the fuel travels obliquely downwardly through the furnace.

Each hollow grate bar is provided with a nozzle 41^a of the form shown in Fig. 6, for 15 the purpose of discharging air below the grate bar. The air thus discharged tends to keep the bottom of the furnace warmer than would otherwise be the case, and mingling with air discharged from the hole 72, 20 passes into the grooves 73, 74, and is thus brought under and into contact with the moving fuel.

Communicating with the header 70 is a pipe 76 which leads to the distributing head 67 and communicates directly with the passage 68 thereof. This pipe is provided with a valve 76^a. Hot air is thus supplied from the header 70 to the nozzle 12 and distributing head 67. The header 67 can 30 be used with or without the pipe 76. When used without this pipe the opening 68 will extend through the wall, into the open air.

Communicating with the pipes 13^a and 76 is a pipe 71^a, having in this instance a 35 Y-form, through which the hot air may be discharged directly into the chimney, or into the open air. By adjusting the valves 71, 76^a, any desired proportion of the hot air arriving through the header may be discharged into the furnace, the residue passing off through the Y-pipe 71^a.

In some instances I may employ the construction shown in Fig. 10.

The distributing head 12^a is given the general form of an arch and is incorporated within the arch 10, as shown in Fig. 1. The distributing head 12^a is provided with a passage 13^a and with jet holes 14^a. No matter whether the nozzle 12 be employed alone 50 or in connection with the distributing head 67, or whether the distributing head 12^a be employed alone or in connection with the nozzle 12 and distributing head 67, hot air is in either case supplied to the furnace at 55 the hottest portion thereof, that is comparatively near the bridge wall.

In the form of my furnace shown in Fig. 8 the arch appears at 78 and the air is supplied through two trunks 42 which branch 60 from a single trunk 79 and extend obliquely upward in opposite directions. With the exceptions noted, the construction in Fig. 8 is similar to that appearing in the other figures.

65 In some instances I may employ a con-

struction of the kind shown in Fig. 9. Here are grate bars 80 each provided with a hollow body portion 81^a, and between these grate bars are other grate bars 83.

A crank shaft 83^a carries a crank 83^b, the latter being journaled to the web 82 of the grate bar 83. The crank shaft is journaled in a bearing 83^c. By turning the shaft 83^a a rocking motion is conferred upon the grate bar 83. In order to admit sufficient air into 70 the furnace to keep up the supply passing through the notches 46 and also between the bars of the dumping grate, I use a door of sufficient size for this purpose, the door being located at the front of the furnace. 75

In Fig. 11 I show a form of my furnace in which the dumping grate is actuated mechanically and is also adjustable at the will of the operator. In this form of my furnace provision is also made for aspirating the air by aid of steam which, becoming dissociated by the heat, supplies hydrogen to the flames. The parts 10, 11, 12, 39, and 40, are similar to the parts above described and bearing these numerals. 80

A wall of the furnace is shown at 84 and supports a header 85 provided with air holes 86. Located in one end of the header is a spider 87 communicating with the open air. A steam jet 85 is supported centrally 95 within this spider. When steam is admitted through the steam jet, it aspirates the adjacent air and carries it through the spider into the header, this air admixed with the steam thence passing through the 100 openings 86.

Angle bars 89 carried by the wall 84 support the header 85. A number of grate bars 90 for the most part similar to the grate bars 36 above described, are severally provided 105 with hollow body portions 91. The top surfaces of these grate bars are provided with raised portions 92 spaced apart, and raised upon these various portions are grate bars 93 arranged as shown. The bars 90 are stationary and the bars 93 are movable. The grate bars 93 are provided with downwardly extending webs 95 and are connected to rocking levers 96, the latter being pivoted to two connecting rods disposed upon opposite sides 115 of the furnace, one of them being shown at 97, these connecting rods being duplicates of each other.

A dumping grate is shown at 98 and is mounted to rock upon pivot pins 99. Pivotally connected with the dumping grate as 120 shown in Fig. 11 is a link 100. This link is pivotally connected with another link 101 by a pin 102. Connected with this pin is a pitman 103 which is pivotally connected with the connecting rod 97. Below the dumping grate is a frame 104, and slidably mounted in this frame is a toothed rack 105. The frame is provided with cross bars 106 serving the purpose of limiting stops. A worm wheel 125

107 is journaled to turn in the frame and meshes with a worm 108. The pinion 107 also meshes with the toothed rack 105. Extending through the worm 108 and rigid 5 relatively to the same is a shaft 109 carrying at its outer end, a hand wheel 110. By turning the hand wheel and thus rotating the shaft, the rack 105 may be moved backward or forward relatively to the frame 104, the 10 relative angular positions of the links 100, 101 being thus shifted accordingly. If desired, any equivalent may be employed for turning the pinion 107 at the will of the operator.

15 When power is applied to the connecting rod 97, the grate bars 93 are actuated relatively to the stationary grate bars 90 and, at the same time the dumping grate is rocked. The adjustment of the dumping grate is thus 20 independent of the motion of the grate bars 94.

In Fig. 12 I show a portion of the mechanism appearing in Fig. 11, but instead of using grate bars of the type shown at 90 in 25 Fig. 11, I employ ordinary flat grate bars 111, Fig. 12, which may, if desired, be provided with the raised portion 113. The movable grate bars are shown at 112 and may be similarly provided with raised portions 114. 30 With this construction I employ an air inlet pipe 115, and render the lower portion of the furnace as nearly as practicable, air tight. In this way the air discharged into the furnace through the inlet pipe 115 passes upwardly between the grate bars and also through the dumping grate as well as between the dumping grate and the header 85.

The mixture of steam and air passing 40 through the holes 86 is heated to a high temperature by exposure to furnace heat before leaving the header 85 and is thrown directly into the flames, and at substantially the hottest part of the furnace.

The operation of my device is as follows: 45 Coal or other appropriate fuel being supplied within the hopper 15 and the parts being arranged as above described, power is applied to the shaft 29. Owing to the action of the eccentrics upon this shaft, the levers 23 and 31 are caused to swing. The feeder head 21 therefore moves in and out and in so doing causes the coal to be fed from the hopper down into the furnace. The connecting rods 50 being moved by aid of the pitman 34, the grate bars 43 are severally caused to reciprocate, each having a lateral sliding movement relatively to the adjacent stationary grate bar 36 at its right, according to Fig. 1. By virtue of the rolling ball 50 52, the grate bars 43 are maintained level, and in being moved are likely to develop but little friction. Air being supplied under pressure into the trunk 42, passes upwardly through the sections 41 and into the hollow body portions 38 of the grate bars. These

grate bars are thus cooled and at the same time the air used in cooling them becomes hot. This air passing outwardly through the pipes 36^a at the ends of the hollow grate bars, enters the header 70 and passing upwardly 70 therefrom is discharged into the furnace through the nozzle 12 and the distributing head 67, or through the distributing head 12^a, as the case may be. A portion of the hot air within the trunk 42 passes downwardly through the member 41^a, as will be understood from Fig. 6, and other portions of the air pass outwardly through the holes 75 72, as above described. The air thus discharged below the bars finds its way upwardly into contact with the fuel, as above described, passing through the semi-cylindrical openings 37^a, 46, and through the grooves 73, 74. The fuel is thus effectively burned by being brought into minute contact with air heated to a high temperature. Such smoke and combustible gases as may otherwise not be consumed are almost inevitably consumed when they reach the hottest portion of the furnace, that is, the portion 80 where the nozzle 12 and the distributing head 67 or the distributing head 12^a, as the case may be, are located. Upon reaching this part of the furnace the smoke and gases mingled with hot air discharged into the furnace, and as this is the point of highest temperature, the combustion is rendered 85 comparatively thorough. The longitudinal movement of the connecting rods 50 by moving the grate bars 43 slowly back and forth in horizontal planes, causes the fuel to be gradually fed downward and so handled as it travels that each particle of it is, so far as practicable, brought into direct contact with the heated air which works up around the 90 grate bars as above described.

With the apparatus above described, the fuel is so distributed and so moved and otherwise handled as to successfully bring it into contact with heated air, freshly supplied to it from the time it leaves the hopper until it reaches the dumping or shaking grate bars 56 where the clinkers and ashes are ejected. By the time the fuel reaches the grate bar nearest the hopper, it becomes coked and as it passes along from one grate bar to another by movements of the movable grate bars relatively to the stationary bars it is evenly distributed as well as thoroughly exposed to the action of hot air.

The normal movement of the movable grate bars tends to maintain a uniform circulation of hot air through the fuel and also to break up such portions of the fuel as tend to run together and to clog.

120 The air cooled grate bars 36 may be used to advantage in all instances where the fuel burns better when supplied with air in addition to that required for maintaining the customary air draft employed in connection 125 130

with such fuel. In instances of this kind the additional air supplied as above described passes upwardly between the adjacent edges of the grate bars and travels 5 through the grooves 73, 74, so as to reach the underside of the moving fuel. Any combustible gases formed from the coal or other fuel employed upon striking the concave face 11 of the arch 10, or coming into close 10 proximity to the same, are effectually burned.

I do not limit myself to the precise arrangement shown as variations may be made without departing from the spirit of my invention, the scope of which is commensurate 15 with my claims.

I claim:

1. In a furnace, the combination of a plurality of grate bars, a dumping grate movable relatively to said grate bars, a link pivotally connected to said dumping grate, another link pivotally connected to said first mentioned link, a connecting rod and a pitman pivotally connected with said connecting rod and with said links for moving said 25 links in order to rock said dumping grate, a rack bar connected with one of said links, a pinion engaging said rack bar, and means controllable at the will of the operator for turning said pinion in order to shift the 30 general angular position of said dumping grate.

2. In a furnace, a plurality of stationary hollow grate bars, each of said grate bars having an upper flat surface, movable grate 35 bars disposed between adjacent stationary grate bars, both the movable and the stationary grate bars having downwardly extending flanges, the flanges on one of said grate bars engaging the upper surface of the 40 adjacent grate bar, the engaging flanges being provided with openings, and means carried by each of said hollow grate bars for supplying air to the openings in said stationary grate bars.

45 3. In a furnace, a plurality of stationary

hollow grate bars, each of said grate bars having an upper flat surface, movable grate bars disposed between adjacent stationary grate bars, both the movable and the stationary grate bars having downwardly extending flanges, the flanges on one of said 50 grate bars engaging the upper surface of the adjacent grate bar, the engaging flanges being provided with openings, and means carried by each of said hollow grate bars for 55 supplying air to the openings in said stationary grate bars, said last named means comprising a series of tubes carried by said stationary grate bars and arranged to extend underneath the top of the adjacent 60 stationary grate bar, said tubes being bent to deliver air toward the openings in the flange of said stationary grate bar.

4. In a furnace, a plurality of stationary hollow grate bars, each of said grate bars 65 having an upper flat surface, movable grate bars disposed between adjacent stationary grate bars, both the movable and the stationary grate bars having downwardly extending flanges, the flanges on one of said 70 grate bars engaging the upper surface of the adjacent grate bar, the engaging flanges being provided with openings, and means carried by each of said hollow grate bars for supplying air to the openings in said 75 stationary grate bars, said last named means comprising a series of tubes carried by said stationary grate bars and arranged to extend underneath the top of the adjacent stationary grate bar, said tubes being bent to 80 deliver air toward the openings in the flange of said stationary grate bar, the upper part of each of said stationary grate bars having grooves arranged to register with the openings in the engaging flanges of the adjacent 85 movable grate bars.

FRANK H. WRIGHT.
